DESIGN FOR A COAT OR SIMILAR ARTICLE

George A. Brunell, Toronto, Ontario, Canada

Application March 30, 1936, Serial No. 61,865

Term of patent 7 years

To all whom it may concern:

Be it known that I, George A. Brunell, a British subject, resident of the city of Toronto, in the Province of Ontario, Dominion of Canada, have invented a new, original, and ornamental Design for a Coat or Similar Article, of which the following is a specification, reference being had to the accompanying drawing, forming part thereof.

Figure 1 is a view illustrating the front of the coat showing the new design.

Figure 2 is a fragmentary side view of the coat depicting more clearly the design of one of the lower side pockets.

Figure 3 is a view of the back of the coat, showing a continuation of the design.

The coat is characterized by a streamline appearance which results from the ornamental curved yokes and seams at 5, 8, 9, 10, 11, 13, 14, 15 and 16, as shown.

I claim:

The ornamental design for a coat or similar article, substantially as shown and described.

Signed at Toronto, Ontario, this 24th day of March, 1936.

GEORGE A. BRUNELL.
